(57) **CLAIM**

The ornamental design for a golf bag, as shown and described.

DESCRIPTION

FIG. 1 is a front perspective view of the golf bag claimed herein;

FIG. 2 is a front elevation view thereof;

FIG. 3 is a rear elevation view thereof;

FIG. 4 is a side elevation view thereof;

FIG. 5 is a side elevation view thereof;

FIG. 6 is a top plan view thereof; and,

FIG. 7 is a bottom plan view thereof.

The broken lines using wide dashes are to show portions of the golf bag and form no part of the claimed design. The broken lines using short dashes are included to show stitching portions of the golf bag and form no part of the claimed design.

1 Claim, 6 Drawing Sheets
